UNITED STATES PATENT OFFICE.

HEINRICH KELLER, OF ZURICH, SWITZERLAND.

REGULATOR.

SPECIFICATION forming part of Letters Patent No. 487,392, dated December 6, 1892.

Application filed April 13, 1891. Serial No. 388,651. (No model.)

To all whom it may concern:

Be it known that I, HEINRICH KELLER, a citizen of the Republic of Switzerland, residing at Unterstrass, Zurich, in Switzerland, 5 have invented certain new and useful Improvements in Regulators, of which the following is a specification.

This invention relates to an improved regulator or governor for motors—for example, 10 steam-engines, water-wheels, and the like; and the object of my invention is to provide a regulator of this kind which is always true and reliable and operates rapidly.

The invention consists in the combination, 15 with a governor and means for rotating the same, of two opposite tapering drums, an endless belt passing around said drums, pivoted levers having forks for guiding and shifting said belt, and means operated from 20 said governor for raising and lowering the belt-levers, a driven shaft, and means for rotating said driven shaft from one of said drums.

The invention also consists in the construction and combination of parts and details, 25 which will be fully described hereinafter, and finally pointed out in the claim.

In the accompanying drawings, Figure 1 is a front view of my improved governor, parts 30 being in section. Fig. 2 is a sectional plan view of the same on the line C D of Fig. 1. Fig. 3 is a vertical transverse sectional view on the line A B of Fig. 1. Fig. 4 is an enlarged detail view of the governor-balls and 35 the cone pulleys or drums. Fig. 5 is a vertical transverse sectional view on the line E F of Fig. 1. Fig. 6 is a horizontal sectional view on the line G H of Figs. 3 and 5, and Fig. 7 is an enlarged detail vertical longitudinal sectional view of the gearing.

Similar letters of reference indicate corresponding parts.

The main shaft *a* is mounted to turn in the journal-bearings *b* *b'* and is provided at one 45 end with a belt-pulley *a'*, or in place of the same any suitable device may be used for rotating the shaft from the motor. By means of the bevel cog-wheels *c* *d* the conical or tapering drum or pulley *g* is rotated from the 50 shaft *a*, and by means of the bevel cog-wheels *e* *f* the vertical governor-spindle *k* is rotated from said main shaft *a*. The tapering drum

g is arranged at one side of the governor-spindle *k* and a like tapering drum *h* is arranged at the other side, said drums *g* *h* being so arranged that the drum *g* has the larger end at the bottom and the drum *h* the larger end at the top, so that the endless belt *i*, passing around said drums, has the same tension whatever position it may have on the drums. 55 The governor-spindle *k* carries a centrifugal regulator *l*, of any well-known construction, provided with the weight *l'*. The upper ends of the governor-levers are pivoted to the governor-spindle *k* and *l'* and their lower ends 60 are connected with the slide *m* and adapted to move vertically.

On the supports *p* the bars *p*² are fastened at the points *p'*, one of the supports having the bars *p*² at the front and the other at the 70 back. To said supports the levers *n* are pivoted, that are provided on their free ends with guide-forks *n*^o for the belt *i*. The levers *n* are connected by the links *m'* with the slide *m*, which is connected with the governor-weight *l'*, so that when the governor-weight moves up or down the said levers *n* will be moved correspondingly and the endless belt *i* is raised or lowered. To prevent the slide *m* from turning, it is provided with 75 an arm *m*², that is mounted to slide up and down in a slot *p*⁴ in the cross-piece *p*³, connecting the supports *p*, as shown in Figs. 2, 3, 5, and 6.

By means of the cog-wheels *q* and *r* rotary 85 motion is transmitted from the drum *h* to the sleeve *s*, on which the bevel cog-wheel *t* is rigidly mounted, said cog-wheel *t* engaging the cog-wheels *u* and *u'*, mounted on the pivots *v* *v'*, projecting in diametrically-opposite 90 directions from the head *v*, keyed on the shaft *w* at the end of the sleeve *s*. The shaft *w* passes from the bearings *y* through the sleeve *s* and has its end *x* mounted to turn in a suitable recess formed in the end of the shaft *a*. 95 Said shaft *w* is to be connected in some suitable manner with the device for controlling the valve of the engine, turbine water-wheel, &c. A wheel *z*, mounted on the end of the shaft *a*, also engages the two wheels *u* and *u'*. 100 The said wheels *u* *u'* are thus acted upon by the wheel *z*, as also by the wheel *t*, and both said wheels *z* and *t* tend to rotate said wheels *u* *u'* in the same direction as long as the belt

i has its normal speed and the drums *g* and *h* make the same number of rotations. The pivots *v'* *v²* do not change their position under these circumstances, and thus no motion 5 is transmitted to the shaft *w*.

In case the speed of rotation of the shaft *a* increases, the governor-balls spread and the driving-belt *i* is raised, so that the drum *h* makes a less number of rotations than the 10 drum *g*. Consequently the bevel cog-wheel *t* will make less revolutions than the wheel *z* and the head *v* will be turned axially a distance proportionately to the difference in speed between the wheels *z* and *t* and will 15 turn the shaft *w*, connected with the valves, &c., of the motor, correspondingly. The diameter of the wheels *u* *u'* thus acts as a simple lever, having its fulcrum on the rim of the wheel *t*, its point of action on the rim of 20 the wheel *z*, and the point at which the power is applied at the pivot *v'*, so that the number of rotations of the head *v* is equal to half the difference in rotations between the wheels *z* and *t*. When the governor-balls descend, the 25 speed of the wheel *t* will be greater than that of the wheel *z* and the head *v* and pivot *v'* and the shaft *w* will be turned in an inverse direction.

Having thus described my invention, I claim as new and desire to secure by Letters 30 Patent—

The combination, with two opposite tapering drums and endless belt passing around the same, of a governor, pivoted levers having forks for guiding the endless belt, means 35 for operating said levers from the governor, a driving-shaft for rotating one of the drums, a driver-shaft in line with said driving-shaft, a sleeve surrounding the driven shaft, means for rotating said sleeve from the other drum, 40 bevel cog-wheels on the driving-shaft and on the driven shaft, a sleeve surrounding the driven shaft, means for rotating said sleeve from the other drum, bevel cog-wheels on the driven shaft and having opposite pivots, and bevel 45 cog-wheels mounted on said head and engaging the bevel cog-wheels on the driving and driven shafts, substantially as set forth.

In testimony whereof I hereunto sign my 50 name, in the presence of two subscribing witnesses, this 20th day of March, 1891.

HEINRICH KELLER.
